UNITED STATES PATENT OFFICE

103,824

DESIGN FOR A SOAP HOLDER

Gahlbeth H. Murrin, Pasadena, Calif.

Application January 25, 1937, Serial No. 67,271

Term of patent 7 years

To all whom it may concern:

Be it known that I, Gahlbeth H. Murrin, a citizen of the United States of America, residing at Pasadena, in the county of Los Angeles and State of California, have invented a new, original, and ornamental Design for a Soap Holder, of which the following is a specification, reference being had to the accompanying drawing forming part thereof.

In said drawing,

I claim:

The ornamental design for a soap holder, as shown.
